Primary Examiner — Ian Simmons*Assistant Examiner* — Samantha Q Lawrence(74) *Attorney, Agent, or Firm* — Whitmyer IP Group LLC(57) **CLAIM**

The ornamental design for a uterine manipulator, as shown and described.

DESCRIPTION

FIG. 1 is a front left side isometric view of a uterine manipulator in accordance with the new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines shown in FIGS. 1-3 and 5-7 illustrate portions of the uterine manipulator that form no part of the claimed design.
